UNITED STATES PATENT OFFICE.

MICHAEL ILJINSKY, OF UERDINGEN-ON-THE-RHINE, GERMANY, ASSIGNOR TO MESSRS.
WEDEKIND & CO. M. B. H., OF UERDINGEN-ON-THE-RHINE, GERMANY.

VAT-DYESTUFF COMPOUNDS SUITED FOR DYEING AND PRINTING.

1,175,634.

Specification of Letters Patent. Patented Mar. 14, 1916.

No Drawing.

Application filed December 13, 1912. Serial No. 736,574.

To all whom it may concern:

Be it known that I, MICHAEL ILJINSKY, chemist, subject of the Russian Emperor, residing at Uerdingen-on-the-Rhine, Germany, have invented new and useful Vat-Dyestuff Compounds Suited for Dyeing and Printing; and I do hereby declare the following to be a full, clear, and exact description of the same.

10 While calcium-leuco-compounds are used extensively in dyeing with indigo, the leuco-compounds of the heavy metals and of those of the alkaline earth metal have heretofore not been employed for dyeing with vat-dyestuffs. In the products containing magnesia which are described in the German Patent 147162, this alkaline earth metal is not present in the form of its hydrate, but as magnesium oxid or burnt magnesia, otherwise they would not be referred to as indifferent fillers. Magnesium hydroxid combines with indigo in its leuco-form. So far, the only leuco-compounds of the heavy metals and of the alkaline earth metals known 25 are those of indigo (confer Georgievics, "Der Indigo", 1892, page 147.) These are exclusively made by double decomposition of the alkaline leuco-compound with metallic salts. My researches in this connection 30 have led to the result, that also other vat-dyestuffs are able to form leuco-compounds with the alkaline earth metals and heavy metals, which are less soluble and more resistant to air than the corresponding calcium-leuco-derivatives. These leuco-compounds are made by either vatting the vat-dyestuffs in their alkaline solution and then adding the desired metallic salt, or by converting the finely suspended vat-dyestuffs 35 into their leuco-compounds in the presence of magnesium-hydrate. In both cases the magnesium-leuco-compounds are precipitated, as they are almost insoluble in water. The formation of these metallic leuco-compounds by double decomposition of their 40 alkaline derivatives with the corresponding metallic salts seems to be a property of all vat-dyestuffs. The conversion of the vat-dyestuffs into their metallic-leuco-compounds by the action of hydrosulfite in the 45 presence of a metallic hydrate is however only possible with indigo, its derivatives and the dyestuffs of the hydron-series, with a few exceptions, as e. g. benzol-1-amino-50 anthraquinone. This peculiar behavior of

the vat-dyestuffs was not to be foreseen, but, as will be seen from the following examples, it offers to the dyers many advantageous methods of using these dyestuffs. As 55 besides hydrosulfite in the presence of compounds of the metallic hydrates does not effect any harmful overreduction of the vat dyestuff in storing, they can in this way be converted into products, which are advantageously used for dyeing either direct or with the addition of more hydrosulfite. The 60 pastes containing the metallic-leuco-compounds are employed either as such or after they have been concentrated or even dried, which is preferably done *in vacuo*. Glycerin, 65 glue, etc., may be added and the proportion of the components may be varied within wide limits.

The dyeing with these leuco-compounds is 70 very simple. It consists in mixing the pastes with water with or without the addition of hydrosulfite and then bringing the goods to be dyed into contact with the suspended leuco-compounds for a longer or shorter time. Generally speaking, with diluted 75 baths weaker dyeings are obtained, and stronger ones with concentrated baths. Also the temperature of the baths is of influence: Cotton absorbs the dyestuff best from cold, 80 wool from warm, and silk from lukewarm suspensions. These leuco-products may also be used for printing and as raw materials 85 for the manufacture of new dyestuffs.

Example 1: 10 parts indigo, 85 parts of a 10% paste of magnesium-hydrate and 15 parts of sodiumhydrosulfite are ground together in a ball-mill to a greenish paste.

Example 2: 10 parts tetrabromindigo 40%, 8 parts magnesium-hydrate-paste 50%, 6 parts hydrosulfite, 2½ parts water are, with the exclusion of air, kneaded together to a greenish tough paste.

Example 3: 10 parts thioindigored, 20 parts magnesiumhydrate-paste 50%, 2½ parts glycerin, 12½ parts hydrosulfite and 5 parts water are, with the exclusion of air, kneaded together to a brown tough paste.

Example 4: 10 parts cibablue B B powder (cibablue is tetrabrome-indigo), 100 parts magnesiumhydrate-paste 10%, 150 parts water and 25 parts hydrosulfite are heated together until the formation of the insoluble yellow-greenish magnesium-leuco-compound is completed. After cooling and filtering, the paste is ready for shipment. 110

Example 5: 10 parts 1-benzoylaminooanthraquinone, 100 parts magnesiumhydrate-paste 10% and 10 parts hydrosulfite are ground together with the exclusion of air.

5 The orangered leuco-compound is separated from the solution by means of a press.

Example 6: 100 parts of a 10% paste of 1.5-dibenzoyldiaminoanthraquinone are vatted with 50 parts caustic soda 40° Bé.

10 100 parts water and 15 parts hydrosulfite. By the addition of a cold solution of 80 parts crystallized magnesiumsulfate in 200 parts water, the magnesium-leuco-compound is thrown down as a voluminous brown precipitate, which is brought into a marketable form by filtering and pressing.

Example 7: 10 parts hydronblue, 200 parts magnesiumhydrate-paste 5% and 10 parts hydrosulfite are ground together with the

20 exclusion of air to a yellow paste which is concentrated by filtering and pressing. In a similar manner, the magnesium-leuco-compounds of hydronviolet (with a copperish brown color) and of hydronyellow (with a brown color) are produced. The reaction is advantageously promoted by heating. Hydronblue or cronblue is a product obtained by sulfurizing indophenol from p-nitroso-phenol and carbazole; its exact chemical

30 composition is unknown.

The leuco-compounds of aluminium, zinc, iron, tin and other heavy metals can be made by double decomposition. The respective dyestuffs are vatted in the presence of

35 an alkali, and a sufficient quantity of the desired salt is added.

The products are marketed either as paste or powder. They are all nearly insoluble in water, their color depends upon the vat-dyestuff, from which they are made, and it is hardly influenced upon by the metallic salt used for their production. To give some examples the color of indigo is greenish-yellow to yellow, of cibablue light green-

ish-yellow, of thioindigo-scarlet 2 G bluish-gray, of thioindigored 3 B greenish brown, of thioindigored B and of tetrabromindigo green, of cibaviolet brown, of benzoylaminooanthraquinone orange-red, of 1.5 dibenzoylaminooanthraquinone brown, of hydronblue 50 yellow, of hydronviolet copperish-brown and of hydronyellow brown.

If exposed to air the products change their color into that of the vat-dyestuffs from which they are made. In case of mixtures 55 the resulting color is a mixture of the colors of the components.

With indigoid vat-dyestuffs in claims 1 and 2, I mean certain vat-dyestuffs similar to indigo, *i. e.* the derivatives of indigo 60 (*e. g.* tetrabromindigo, ciba blue, ciba violet) the thioindigo dyestuffs (*e. g.* thioindigo red, thio-indigo violet), the vat-dyestuffs of the hydron series (*e. g.* hydron blue, hydron violet, hydron yellow), 1-benzoylaminooanthraquinone, 1.5-dibenzoylaminooanthraquinone. 65

The alkaline earth metals mentioned in the description and the claims can be substituted by the earth metals, the light metals 70 or the heavy metals but not by the alkaline metals.

I claim:

1. The herein described new composition comprising a leuco-compound of a derivative of indigo with alkaline earth metals which compound is almost insoluble in water and suited for dyeing and printing. 75

2. The herein described new mixture of a composition comprising a leuco-compound 80 of a derivative of indigo with alkaline earth metals, and of hydrosulfite, which compound is almost insoluble in water and suited for dyeing and printing.

In testimony whereof, I have signed my 85 name to this specification.

MICHAEL ILJINSKY.
